UNITED STATES PATENT OFFICE.

PAUL A. CHAMBERLAIN, OF CHICAGO, ILLINOIS, ASSIGNOR, BY DIRECT AND MESNE ASSIGNMENTS, TO ELECTRICAL DEALERS SUPPLY HOUSE, INC., OF CHICAGO, ILLINOIS, A CORPORATION OF ILLINOIS.

RADIOCONDENSER.

Application filed July 2, 1924. Serial No. 723,617.

To all whom it may concern:

Be it known that I, PAUL A. CHAMBERLAIN, a citizen of the United States of America, and a resident of Chicago, Cook County, Illinois, have invented a certain new and useful improvement in Radiocondensers, of which the following is a specification.

This invention relates to improvements in multiple circuit controlling devices for radio apparatus and more particularly to condensers adapted for use in multiple circuits and has for its principal object to provide an improved form of apparatus of the class described in which two or more condensers each coupled in a separate circuit, as for instance, in successive amplification stages of a radio receiving or sending set, may be all adjusted and the respective circuits balanced so as to afford simultaneous control of the circuits by manipulation of a single controlling member.

For the purpose of illustrating my improved apparatus, I have shown it as applied to a standard hook-up for amplification of radio-frequency currents in a radio receiving set in which the separate audion amplification circuits are tuned by varying the capacities of each grid circuit. It is well known by those familiar in the art that the advantages of controlling such condensers by a single controlling device are self evident, yet it has been found quite difficult to produce satisfactory unitary control apparatus of this character in commercial quantities for the reason that several variable and uncertain factors are established during construction of each apparatus, which factors are not subject to ready control or measurement, even though great care be exercised to conform to uniform specifications and standards of construction. These factors will be hereinafter more fully discussed in connection with my improved means and method of offsetting the combined effects of such factors.

My invention contemplates the provision of a novel arrangement of circuits and method of adjusting the same, wherein means are provided for independently adjusting the capacities of a plurality of condenser units which adjustment is made after the apparatus is wired and completed so that the circuit condensers and their re-

spective circuits are balanced or phased to the same periodicity with respect to each other. This balancing of the several capacities will offset the combined effects of the several uncertain and variable factors already suggested. Another feature of the invention is the provision of means for shielding the several condenser units from each other thereby permitting such units to be mounted in relatively close relationship with each other, as for instance, in axial alignment with each other on a common shaft, thereby eliminating the effect of capacity coupling between the separate circuits at this point.

The invention may be best understood by reference to the accompanying drawings in which:

Figure 1 is a plan view of one form of condenser construction in accordance with my invention.

Figure 2 is a side view of the condenser shown in Figure 1.

Figure 3 is an end view of the condenser shown in Figure 1 with a part broken away to show one end of a shielding plate.

Figure 4 is a section taken on line 4-4 of Figure 3.

Figure 5 is a plan view of a modified form of condenser in this form the balance and shield adjusting plate is movable with the roller.

Figure 6 is an end view of the condenser shown in Figure 5.

Figure 7 is a detail taken on line 7-7 of Figure 5.

Figure 8 is a diagram showing a typical application of my invention to a portion of a radio frequency amplification apparatus.

Fig. 9 is an enlarged diagram of the condenser construction.

Referring now to details shown on the drawings, Figs. 1 to 4 illustrate a preferred form of condenser which may be used in carrying out my invention. This condenser comprises a frame consisting of metal end plates 10-11, a pair of oppositely disposed connecting rods 12, 12 preferably threaded as shown and extending between the upper corners of the end plates 10, 10 and secured thereto by suitable means such as nuts 13, 13. A third connecting member may connect the lower margins of the end plates centrally thereof; as shown herein this con-

necting member comprising a rod 16 secured to the end plates by screws 17, 17. The structure is provided with a plurality of condenser units; in the form illustrated here-
 5 in two such condenser units 18 and 19 are shown, the first of which consists of a stator made up of a plurality of parallelly disposed plates 21, 21 spaced apart, and a rotor element made up of a plurality of plates 23, 23 interposed between adjacent stator plates. This condenser unit therefore comprises an air gap condenser of the usual construction, the stator plates being substantially rectangular and the rotor plates being semi-circular in shape. The rotor plates are rotated so as to vary the capacity of the condenser in the usual manner. The second unit 19 consists of a similar arrangement of stator plates 25 and rotor plates 26. In the form of condenser shown in figure, the stator plates 21, 21 of condenser unit 18 are insulated from the condenser frame by suitable means, as, for instance, they are mounted on insulator blocks 30—30
 15 supported on rods 31—31. Similarly, the second condenser unit 19 is mounted on the frame by a similarly disposed pair of insulator blocks 32—32 disposed adjacent the opposite ends of the supporting rods 31—31.
 20 A preferred form of mounting for the insulator is shown herein in detail in Figure 4. In this construction the supporting rods 31—31 are passed through each of the insulated blocks 30—30 and having their full
 25 diameter fitting closely in supporting engagement for a limited portion thereof, as for instance, adjacent the sides of the blocks, while the intermediate portion of said supporting rod is reduced in diameter as indicated at 33 thus providing a limited contact between the supporting rod and the insulating block to reduce electrostatic losses between the stator plates and the frame to a minimum. The stator plates may be supported on the insulator blocks 30—30 by any suitable means, for instance, in Fig. 3, it will be seen that said plates are secured to pieces 34, 34 of conducting material, as for instance by welding, said block pieces being mounted on the inner faces of the insulator 30—30 by means of screws 35—35. Termi-
 30 nals 36—36 provide connection for the respective stator elements of condenser units 18 and 19.
 35 The rotor plates of condenser units 18 and 19 are mounted on the common shaft 40 in the usual manner and the shaft has bearing in end plates 10 and 11 by any suitable means, as, for instance, the bearing on plate 10 consists of a ball bearing 41 adjustable by a screw 42, while the opposite end of the shaft is provided with a split threaded bearing 43 adjustable by a nut 44 to vary the tension on the shaft in the usual manner.
 40 The shaft is provided by a prolongation 45

adapted to extend through a panel 46 in the usual manner for connection to a dial or similar manual adjusting device.

Referring now to the particular features of novelty forming a part of my invention, it will be observed that I provide an electrostatic balancing adjustment between adjacent condenser units. The balancing means consists of a pair of plates 50 and 51, interposed between and adjustable toward and away from the plates of the adjacent condenser units 18 and 19. In the form shown in Figures 1, 2 and 3, these balancing plates are substantially the same as the rotor plates in general outline and are given their lateral adjustment by thumb screw mountings at opposite sides of the condenser. These mountings consist herein of a pair of thumb screws 52—52 threaded on the supporting rods 31, 31 and having annular slots 53, 53 in which recessed portions 54 of the balance plates are carried. As will be seen from the drawings, the plate 50 may be moved toward and away from the adjacent condenser unit 18 as desired, while the other plate 51 may be similarly adjusted with relation to the opposite condenser unit 19. In case more than two condenser units are employed, it will be understood that similar balancing plates may be interposed between each pair of adjacent condenser units.

Referring now to the use and operation of the condenser units just described, Figure 8 is a diagram showing a portion of a typical audion amplification apparatus in which the grid circuits of successive amplification stages are adapted to be tuned by means of shunt condensers. In the particular diagram illustrated, I have shown connections for portions of two stages of radio-frequency amplification. The grid circuit of the first stage includes the grid 60 in an audion 61, a grid lead 62 to a secondary coil 63 of an input transformer 59. A grid return lead 64 connects said secondary coil to a negative filament lead 65 of audion filament 66. This negative lead connects with the negative side of A battery 67 and may also go to ground 68. The plate circuit of the first audion includes the plate 70 and its lead 71 to primary 72 of transformer 73, thence by lead 74 to plus side of "A" battery 67 through "B" battery 75. The filament 66 connects with plus A battery through rheostat 78 and leads 77 and 79. The second audion 80 has similarly arranged grid and plate circuits, the grid circuit including the secondary coil 81 of the transformer 73, grid lead 82, and grid return 83. The plate circuit constitutes an output in the usual manner.

The use and application of the improved type of condenser units will now be described.

One of the commonly used methods of

tuning successive amplifying stages as herein illustrated is by means of condensers shunted from the grid lead to the grid return lead of each grid circuit.

5 Among the principal factors which have been shown to effect the tuning of the separate circuits are (a) the electrostatic capacity of each circuit. This depends upon the relation of the several leads and other 10 parts of the circuit and may vary considerably as between circuits, even though considerable diligence is utilized in the construction and arrangement of the leads, and other parts thereof; (b) electrostatic capacity between successive or adjacent stages or parts thereof. Here again, considerable variation may be caused between the capacities of adjacent stages. (c) There are also 15 electromagnetic effects in each stage caused by the relation of coils and leads thereof either in the grid circuit, plate circuit, or both circuits of each stage. (d) There is furthermore, electromagnetic coupling between adjacent stages which has considerable 20 effect in varying the inductances of the several stages. (e) There also may be variations due to differences or defects in the apparatus employed in successive stages, including the differences in capacity of audions, thus making it extremely difficult to 25 assure the desired uniform capacity and inductance values to be controlled by the condensers. Capacities of the condensers themselves may vary somewhat. (f) The resistance values may also vary considerably as 30 between separate circuits or stages, as, for instance, in the case of defective connections, contacts, etc. Furthermore, experience demonstrates that it is extremely difficult to 35 detect the controlling elements which cause these various differences in each particular 40 instance.

From the above discussion of the many 45 variable factors, it will be now understood why it is generally considered impracticable to control all of these factors with such degree of certainty as to insure uniform 50 changes in several condenser units used to tune the separate circuits of the apparatus, even though these condensers be exactly 55 equal in capacity. In other words, it has been demonstrated that these factors are established during the manufacture of the apparatus, and vary so greatly with each set, that it has been found practically impossible 60 to secure substantial uniform tuning effects in the separate circuits by varying separate condensers uniformly, even though the condensers are of substantially the same capacity.

For these reasons it has usually been the practice to tune each of such amplification stages by means of independently operated condensers.

65 My improved form of condenser including

balancing and shielding means as described is designed to provide an adjustment to readily compensate for the varying factors above discussed. In the typical circuit shown in Figure 8 this is accomplished as 70 follows:

The stator of condenser unit 18 is connected by lead 86 to grid lead 62 of the first amplifying circuit, and the second condenser unit 19 is connected by lead 87 to grid lead 75 82 of the second amplifying circuit. The rotor 40 of the condenser is connected through lead 45 to the grid return lead 64 which is in turn connected to both minus filament leads of the two amplifying stages. 80 Since the grid return lead 83 is also connected to the second minus filament lead, the rotor 40 thus provides a common connection to the two grid return leads, and furthermore, provides a common ground at 85 68, when such ground connection is used.

Now, when the circuit is fully completed, the inductance and capacity values of the first and second stage grid circuits usually 90 vary from their desired equal ratios, due to the effect of the several factors hereinbefore discussed. By the provision of the adjustable balancing plates 50 and 51, however, the relative capacities of the two condenser units and their respective circuits may be 95 balanced to approximate equality, and thus bring their respective circuits into phase or resonance at all points of tuning by various means, the simplest method being that of tuning the set to receive a given signal, and then adjusting the two balancing plates so 100 that the critical point of maximum tuning of each circuit coincide at one position of the rotor. In other words, said plates are adjusted so that the points of maximum 105 volume of the separate amplifying stages are coincident on the single tuning dial of the condenser. This adjustment may be 110 readily made by anyone skilled in the art, and once made, no further adjustment is necessary for all ranges of the two condenser units, so long as the internal capacity and inductance values of the separate circuits remain unchanged. This semi-permanent adjustment of capacities of the two condenser units 18 and 19 is indicated in 115 Figure 8 by the dotted arrows, while the full arrow indicates that the entire condenser including said units 18 and 19 may be varied by a single adjusting means such as a dial, to tune the set to various frequencies or wave lengths in the usual manner.

In the enlarged diagram in Figure 9 the construction of the condenser is illustrated 125 in greater detail showing diagrammatically the arrangement of the separate elements of the condenser units 18 and 19 including the rotor plates, stator plates and balancing plates.

It will further be observed that the balancing plates form an effective shield against capacitative effects between the adjacent condenser units 18 and 19 because the 5 said plates have common connection with the rotor and with the grid return leads 64 and 63, as well as ground 68. The intercapacity effects between separate circuits at this point are therefore reduced to a minimum 10 making it possible to mount the condenser units relatively close to each other. This is of especial advantage where a common rotor shaft is employed, and it is desired that the overall length of the condenser 15 be restricted to compact limits.

In the form shown in Figures 5 and 6, I have shown a modified form of condenser which may be used in carrying out my invention.

20 In this form, the balancing plates are carried upon the rotor instead of being carried upon the condenser frame as in the first form herein described.

25 In the second form of condenser, the frame comprises a pair of insulated or non-conducting end plates 90 and 91. The condenser units 18^a and 19^a each comprises stator plates 94, 94 supported in spaced relation on a plurality of supporting bars 92 30 and 95. The bars 92 are supported on the end plate 90 and the opposite bars 95 are supported on end plate 91. In this form of condenser the condenser units are insulated from each other by providing insulating members 96, 96, in alignment with each pair of supporting bars 92 and 95. These bars have reduced end portions 92^a and 95^a extending in the opposite ends of the holes 98 in the insulating members and 35 spaced apart therein, as shown in Figure 7. The entire frame is clamped together by a securing means such as rods 99, 99 spaced from the stator plates as best shown in Figure 6. The rotor comprises two sets 40 of rotor plates 100 and 101 of the usual semi-circular form carried on the shaft 40^a in the usual manner. These sets of rotor plates are interleaved with the stator plates of the respective condenser units 18^a and 45 19^a in the usual manner. The balancing plates 50^a and 51^a are mounted for longitudinal adjustment on the threaded portion 107 of the shaft 40^a intermediate the condenser units 18^a and 19^a. This adjustment 50 is afforded by suitable means such as threaded members 97, 97 and lock nuts 108, 108 associated therewith. In this form of condenser the balancing plates are preferably circular in shape as shown, inasmuch 55 as they are movable with the rotor and it is desirable to have these plates interposed between adjacent stator plates in all positions of the rotor so as to provide uniform capacity coupling between said plates and 60 condenser units as well as the desired shield-

ing of the condenser units from each other.

It will be manifest that in case only two circuits, including their respective condenser units, are employed, the desired balancing may be accomplished as between the two units by the use of a single balancing plate, although for best results a finer and quicker adjustment is afforded by the two plates as shown in the preferred form illustrated herewith. Furthermore, it is manifest that more than two circuits can be balanced by providing each circuit with separate condenser units having a common rotor and all controlled by a single dial, but with balancing plates interposed between each pair of adjacent condenser units for adjusting the respective values, in the manner already described in connection with two such condenser units.

It will be understood that my invention 85 is not limited to the tuning of successive grid circuits as illustrated herein, but is capable of the use in many variations of radio apparatus, in which it is desired to vary several capacities in substantially uniform decrements, while compensating for the uncertain variable factors of distributive capacity, etc., established in the manufacture of each set.

90 I claim:

1. In an apparatus of the class described, a condenser provided with capacity elements movable relative to each other, one of said elements comprising a plurality of insulated units, and means interposed between adjacent units and conductively connected to the other of said elements, and adjustable in position relative to said insulated units to vary their respective capacity ratios.

2. A condenser comprising a frame, a 105 rotor and a stator, the stator being divided in a plurality of condenser units insulated from each other and spaced longitudinally of said rotor, and means electrically connected with said rotor and interposed between adjacent condenser units for shielding said units from effects of intercapacity coupling therebetween.

3. A condenser comprising a frame, a rotor and a stator, the stator being divided 110 in a plurality of condenser units insulated from each other and spaced longitudinally of said rotor, and means electrically connected with said rotor and interposed between adjacent condenser units, said means 115 being independently adjustable toward and away from their respective units to vary their capacity ratios.

4. In an apparatus of the class described, a condenser comprising a frame, a plurality 125 of stator units supported on said frame in spaced relation and insulated from each other, a rotor comprising a plurality of members each cooperating in capacitative relation with said stator units, and balancing 130

means mounted on said rotor intermediate adjacent condenser units and adjustable longitudinally of said rotor.

5. A variable capacity device comprising a plurality of condenser units, each unit having a rotor element and a stator element, common means for operating the rotor element of each unit, a conductive plate, in addition to said elements, and means for 10 supporting said plate between said units and for adjusting the same along the rotor axis.

6. A variable capacity device comprising a plurality of condenser units, each unit 15 having a rotor element and a stator element, a common means supporting a similar one of said elements in each unit and a conductive plate between said elements and adjustably supported by said common means.

20 7. A variable capacity device comprising a plurality of condenser units, each unit having a rotor element and a stator element, a screw threaded means supporting a similar one of said elements in each unit and a conductive plate between said elements and adjustably supported by nuts clamping the same to said means.

8. A variable capacity device comprising a plurality of condenser units, each unit 30 having a rotor element and a stator element, common means for operating the rotor element of each unit, a pair of conductive plates, in addition to said elements, and means for supporting said plates between 35 said units and for adjusting the same along the rotor axis relative to each other and to the said unit.

9. A variable capacity device comprising a plurality of condenser units, each unit having a rotor element and a stator element, a common means supporting a similar one of said elements in each unit and a pair of conductive plates between said elements and adjustably supported by said common means.

45 10. A variable capacity device comprising a plurality of condensers each having a rotor and a stator, common means for operat-

ing all said rotors in unison, and a conductive plate interposed between the condensers and adjustably spaced along the 50 common rotor axis from the stators thereof.

11. A multiple variable capacity device comprising a frame, a plurality of stators carried in spaced relation by said frame, a shaft mounted for rotation in said frame, a 55 plurality of rotors carried by said shaft and each cooperating with a corresponding one of said stators to provide a variable capacity upon rotation of the shaft, thus constituting a plurality of condenser units, and additional condenser elements disposed between, and arranged to cooperate with, said condensers, to shield them from one another and adjustable to vary slightly the relative capacities 60 of the condensers. 65

12. A condenser comprising a frame, a plurality of stator units spaced longitudinally of said frame, rotor units in capacitative relation with said stator units and mounted on a common shaft, each pair of 70 stator and rotor units having cooperating surfaces in capacitative relation with each other of area substantially equal to cooperating surfaces of the other pairs of stator and rotor units, and all of said capacity 75 areas being variable in uniform decrements as said common rotor is rotated, and means, associated with each pair of said rotor and stator units and electrically common with one of said units, permitting relative movement of a capacitative area toward and away 80 from a cooperating capacitative area of the other unit in a direction parallel with the axis of rotation of said common rotor units, whereby the capacity ratios of said rotor and 85 stator units may be independently varied, but the angular relation between each set of rotor and stator units will be uniform for all pairs thereof in any position of rotation of said common rotor. 90 95

Signed at Chicago this 25th day of June, 1924.

PAUL A. CHAMBERLAIN.
